(57) **CLAIM**

The ornamental design for a vehicle centre console, as shown and described.

DESCRIPTION

FIG. 1 is a front left elevated perspective view of a vehicle centre console according to the present invention.

FIG. 2 is a front left perspective view of the vehicle centre console shown in FIG. 1.

FIG. 3 is a rear right elevated perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof.

FIG. 11 is a front left elevated perspective view of a vehicle centre console according to a second embodiment of the present invention.

FIG. 12 is a front left perspective view of the vehicle centre console shown in FIG. 11.

FIG. 13 is a rear right elevated perspective view thereof.

FIG. 14 is a rear right perspective view thereof.

FIG. 15 is a front view thereof.

FIG. 16 is a rear view thereof.

FIG. 17 is a left side view thereof.

FIG. 18 is a right side view thereof; and,

FIG. 19 is a top view thereof.
